UNITED STATES PATENT OFFICE

105,974

DESIGN FOR A COMBINED ASHTRAY AND CIGARETTE EXTINGUISHER

Albert A. Vuccino, New York, N. Y.

Application July 17, 1937, Serial No. 70,503

Term of patent 7 years

To all whom it may concern:

Be it known that I, Albert A. Vuccino, a citizen of the United States, residing in the Borough of Manhattan, city of New York, county of New York, and State of New York, have invented a new, original, and ornamental Design for a Combined Ash Tray and Cigarette Extinguisher, of which the following is a specification, reference being had to the accompanying drawing, forming part thereof.

I claim:

The ornamental design for a combined ash tray and cigarette extinguisher as shown.

ALBERT A. VUCCINO.
